APPARATUS FOR ALIGNING WHEELS

Michael Miller, Trenton, N. J.

Application June 5, 1931, Serial No. 542,445

10 Claims. (Cl. 83—203)

My invention is an improvement in apparatus for aligning the wheels of motor vehicles, and is designed to provide a portable apparatus or device of this general character which will operate automatically when the wheels are driven on to the same to indicate whether or not they are out of alignment, and which will also serve to facilitate the operation of adjusting the wheels if required.

With these ends in view my invention consists of a pair of wheel supporting blocks rotatable on a suitable base with means by which to accommodate the track or tread of the wheels and gauges to indicate their alignment, for which purpose the said blocks are mounted on carriages for lateral movement on the base and rotatable on the carriages for free turning movement, thereby providing a device or apparatus for quickly and conveniently ascertaining whether or not the wheels are out of alignment, and the extent to which any required adjustments should be made.

My invention further consists in the particular construction of the supporting blocks and manner of supporting the same on the base, in cooperation with the construction and arrangement of gauge devices, all as hereinafter fully described and more specifically set forth in the appended claims.

In the drawings:—

Figure 1 is a front elevation illustrating the application of my invention.

Fig. 2 is a plan view of the apparatus.

Fig. 3 is a front elevation, enlarged, parts being in section.

Fig. 4 is a detail plan view of the supporting base, with parts of the superstructure removed.

Fig. 5 is a detail plan view of one of the rotatable blocks.

Fig. 6 is a bottom view thereof.

Fig. 7 is a longitudinal sectional view through the center of the block, and

Fig. 8 is a transverse sectional view on the line 8—8 of Fig. 5.

In carrying out my invention I employ a suitable base 10, preferably constructed of metal to provide an elongated platform with depending marginal edges forming end supports 11 and intermediate supports 12, part of the platform being cut away as shown in Fig. 4 to reduce the weight of the base which is designed for the purpose of supporting spaced apart blocks 13 rotatably mounted on carriages 14, the latter being movable on the base longitudinally with respect thereto and laterally with respect to the wheels

seated in the blocks for the accommodation of these movable parts with respect to the trackage of said wheels. Each carriage is slidably mounted on rollers 15 supported on axles 16 journaled in the side flanges of the base, and for connecting the block 13 to the carriage 14 so that it may have the required rotatable movement thereon it is provided centrally with a depending pintle 17 extending through a corresponding opening 18 in the floor of the carriage and through a slot 19 in the platform or base, said pintle having a hole 20 extending transversely through the lower end thereof to receive a key 21. As will be noted the block is rotatable on the carriage by reason of the bearing of the pintle in the opening 18 and movement of the carriage on the base permitted by the slot therein through which the pintle passes, and in order that the block may have a free rotatable movement on the carriage so as to easily adjust itself to the position of the wheels supported thereon said carriage is provided on its upper side with ball bearings 22 in a circular cage 23 to bear in a runway 24 at the under side of the block, though it may be desirable to reverse this arrangement by having the balls 25 carried by the block instead of the carriage. Any shape of block to receive the wheels of the automobile may be employed but in order to effect a positive or firm engagement the form of block shown in the drawings is well adapted, being constructed to provide ramps or inclined runways 26 at opposite ends leading to a depressed seat 28 at the center, as clearly shown in Fig. 7, with upstanding side pieces or guiding members 27 and 29 at opposite sides of the runways and seat, 35 the side piece 27 being vertical and having an inwardly projecting portion or rib 29 at its upper inner edge while the inner wall of the opposite side piece 28 is inclined outwardly from the seat, whereby said inclined wall will cause the tire of the wheel to be pressed or wedged against the rib to properly position the wheel with respect to the block, and for indicating the alignment of the blocks and corresponding alignment of the wheels of the automobile mounted thereon said 45 blocks are each provided with a suitable gauge, in the present instance gauges being located at the opposite sides thereof.

In the normal position of the swivelled blocks they are at right angles to the medial line of 50 the supporting base, as shown in Fig. 2, the blocks being temporarily held in this position by a pin 30 passed through a hole in a projection 31 at the outer side of the block and through hole 32 in the carriage, and for indicat- 55

ing any variation of the block in either direction from the right angular position said projection 31 at the side of the block is provided with a pointer 34 cooperating with a dial 35 at the 5 adjoining edge of the carriage. As will be obvious when the wheels of an automobile are run on to the spaced apart swivelled blocks so as to be wedged between the parallel side walls, which are in direct line with the length of the block at 10 opposite sides of the seat, any variation in the alignment of either one or both of said wheels will be indicated by the pointer 34 moving over the dial 35 having suitable graduation marks, and for holding the apparatus or device while the 15 wheels are being run up the incline on to the seats of the blocks the outer end of each incline is provided on its under side with sharp points or pins 36 which dig into the floor and steady the blocks.

20 For connecting the carriages so that the swivelled blocks carried thereby may accommodate themselves to the tread or trackage of the automobile wheels narrow plates 37, 37 are attached to and extend from the inner ends of the 25 carriages being pivoted at their outer ends to a set of toggle links 38, the crossed links at the center being pivoted by pin 39 to the platform or supporting base and the plates guided to maintain their longitudinal movement on the 30 base by means of metal fixtures 40 secured to said base. These connecting plates in addition to cooperating with the toggle links in equalizing the blocks also provide a means for supporting one of the elements of an auxiliary gauge for 35 each block consisting of a gauge-plate 41 attached to the outer end portion of the connecting plate and bent over the adjoining toggle links, said gauge-plate cooperating with a pointer 42 in the form of a tubular rod fitted 40 within a recess therefor at the inner side of the block, whereby the gauge-plate and pointer of each block will be in fixed relation thereto irrespective of the movement of the blocks to or 45 from each other in accommodating the tread or trackage of the automobile wheels, and of course the toggle link connection between the plates will serve to position the blocks at equal distances from the center of the supporting base.

50 In the operation of the device the automobile wheels to be tested are run on to the blocks which latter will move on the carriages or be separated automatically according to the tread of the wheels, and when the pins 30 are removed said blocks will assume the alignment corresponding with that of the wheels as the vertical wall impinges against one side of the tire of the wheel for this purpose, the extent to which either one of the wheels is out of alignment being indicated by the gauges at the inner and outer sides of said blocks. A wheel which is out 55 of alignment can be trued while resting on the block supporting the same and of course the gauges will indicate when the proper adjustment has been made to bring said wheel into alignment. It will thus be seen that the operation of testing the alignment of the wheels of automobiles can be quickly effected by the use of my improved device, and that it also facilitates the operation of truing or aligning the wheels as the adjustments being made are indicated by the gauges during the operation of aligning.

75 The device in accordance with my invention

provides a simple and effective means for aligning the wheels of automobiles and by the particular construction and arrangement of the parts the device may be disassembled for handling in moving the same from place to place, the blocks 5 being detachable from the carriages and base by removing the keys 21 at the lower ends of the spindles and the carriages with their connections can be removed if necessary by detaching the pin 39 and metal fixtures which hold and 10 guide the plates on the platform of the supporting base. The several parts thus disconnected can be easily handled in moving the device from one place to another, and for storage or transportation the blocks only need be removed so 15 as to be stored separately or placed lengthwise on the base for more compact arrangement.

I claim:—

1. An apparatus for aligning the wheels of motor vehicles comprising a supporting base, a pair 20 of elongated wheel supporting blocks swivelled thereon, walls on the upper side of each block at opposite sides thereof, one of said walls being outwardly inclined and the other vertical, and between which the wheel is wedged in alignment 25 with the block so that the latter will assume the alignment of the wheel bearing against the vertical wall of said block, a depressed seat at the center of the block between said walls, and ramps formed integrally with the block at opposite 30 ends thereof, said ramps leading to the seat; together with means for indicating the turning movement of the blocks.

2. An apparatus for aligning the wheels of motor vehicles comprising a supporting base, a pair 25 of elongated wheel supporting blocks swivelled thereon, walls on the upper side of each block at opposite sides thereof between which the wheel is wedged, one of said walls being outwardly inclined and the other vertical with a 30 longitudinal rib at its upper inner edge, ramps leading to the space between said walls, and spurs at the corners of the block; together with means 35 for indicating the turning movement of the blocks.

3. An apparatus for aligning the wheels of motor vehicles comprising a supporting base, carriages 50 slidable on said base and each having a hole therein to receive a coupling pin, a block swivelled on each carriage for turning movement 55 and each having an apertured projection at one side thereof, and a pin for temporarily connecting each block to its carriage; together with means for indicating the turning movement of the blocks.

4. An apparatus for aligning the wheels of motor vehicles comprising an elongated supporting base, carriages slidable on said supporting base at opposite ends thereof, means connecting 60 the carriages for equalizing their sliding movement with respect to the center of the supporting base, a block swivelled on each carriage and having a seat to receive a wheel of the motor vehicle, and means for indicating the turning 65 movement of the blocks.

5. An apparatus for aligning the wheels of motor vehicles comprising an elongated supporting base, carriages slidable on said supporting base at opposite ends thereof, means connecting 70 the carriages for equalizing their sliding movement with respect to the center of the supporting base, a block swivelled on each carriage and having a seat for a wheel of the motor vehicle with ramps leading to said seat, a dial on each car- 75

riage, and pointers on the blocks cooperating with said dials for indicating the turning movement of said blocks.

6. An apparatus for aligning the wheels of motor vehicles comprising an elongated supporting base, carriages slideable on said supporting base at opposite ends thereof, toggle levers pivoted on the base intermediate the carriages, and plates connecting the carriages to said toggle levers; together with a block swivelled on each carriage and having a seat to receive a wheel of the motor vehicle, and means for indicating the turning movement of the blocks.

7. An apparatus for aligning the wheels of motor vehicles comprising an elongated supporting base, carriages slideable on said supporting base at opposite ends thereof, toggle levers pivoted on the base intermediate the carriages, and plates connecting the carriages to said toggle levers for equalizing the movement of the carriages; together with an elongated block swivelled on each carriage and having a central depressed seat with ramps extending from opposite ends of the block to said seat, and means responsive to the turning movement of the blocks for indicating the alignment of the wheels supported thereby.

8. An apparatus for aligning the wheels of motor vehicles comprising an elongated supporting base, carriages slideable on said supporting base at opposite ends thereof, toggle levers pivoted on the base intermediate the carriages, plates connecting the carriages to said toggle levers for equalizing the movement of the car-

riages, and a gauge plate or dial attached to each connecting plate; together with a swivelled block on each carriage, and a pointer extending from the block to cooperate with its companion gauge plate or dial.

9. An apparatus for aligning the wheels of motor vehicles comprising a supporting base, an elongated wheel supporting block turnable on said base, upstanding walls at opposite sides of said block, one of said walls being inclined outwardly and the other wall being straight vertically for clamping the wheel tire between said walls and against the vertical wall so as to be parallel therewith for positioning the wheel in alignment with the turnable block, an end of each wall being flared outwardly to form guide walls leading to the space in which the wheel tire is clamped; together with means for indicating the turning movement of the block.

10. An apparatus for aligning the wheels of motor vehicles comprising a supporting base, an elongated wheel supporting block turnable on said base, upstanding walls at opposite sides of said block, one of said walls being inclined outwardly and the other wall being straight vertically with a longitudinal rib at the upper end of the inner side thereof, for clamping the wheel tire between said walls, an end of each wall being flared outwardly to form guide walls leading to the space in which the wheel tire is clamped; together with means for indicating the turning movement of the block.

MICHAEL MILLER.
